(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front image for a display screen or portion thereof with graphical user interface showing our new design; and, FIG. 2 is an enlarged front view of the graphical user interface of FIG. 1.

The broken-line outline of a circle shown with a short-and-long dash pattern in FIG. 1 illustrates the bounds of the enlargement shown in FIG. 2 and forms no part of the claimed design.
